UNITED STATES PATENT OFFICE

JAMES CHESTER BROWN, OF NEW YORK, N. Y., ASSIGNOR, BY MESNE ASSIGNMENTS,
TO E. FREDERICKS, INC., OF NEW YORK, N. Y., A CORPORATION OF NEW YORK

PAD

Application filed January 19, 1928. Serial No. 247,817.

This invention relates to a pad of improved construction, and specifically aims to provide a device of this character primarily intended for use in connection with the permanent waving of hair.

It is an object of the invention to furnish such a pad which will embody few parts and may be economically and readily constructed by relatively unskilled labor and which may be employed with facility in the process of permanent waving.

A further object is that of constructing an article of this type which will be of such a nature that it may be employed in but a single operation. As a consequence, the pad may be furnished by the manufacturer to the operator in sterile condition and, when once employed by him, will be discarded so that all objections which have arisen in connection with the repeated using of articles of this nature are avoided, aside from the fact that by this expedient a pad in proper condition will always be presented at the initial stage of the operations, thus assuring most desirable results.

An additional object is that of furnishing a device of this character which will have maximum qualities of absorption so that adequate treatment of the hair may be effected during the permanent waving operation.

With these and further objects in mind, reference is had to the attached drawings in which are illustrated practical embodiments of the invention and in which:

25 Figure 1 is a face view of a pad;

Fig. 2 is a partly sectional view showing the pad in use;

Fig. 3 is a view corresponding to Fig. 1 and showing a slightly different form of pad; and

40 Fig. 4 is a perspective and slightly exaggerated view of pad portions as constructed in Fig. 3.

By means of the present invention, it is intended that a sanitary pad be provided which, in certain aspects, will be self-destructive. In other words, the material of the pad will be affected detrimentally by the conditions of moisture and temperature to which it is subjected during treatment so as to 50 render it unsuitable for further use.

Additionally, a pad of the present invention is to be constructed economically, and preferably to embody highly absorbent qualities, so that it may retain to a maximum extent fluid which enters into the treatment. Specifically, it is intended to employ pulp paper which may be arranged in the form of one or more layers. This material, being of a highly digested nature, will embody, to a maximum extent, qualities of fluid absorption. Furthermore, such material lends itself, in manufacture, to having incorporated in its body a suitable chemical or chemicals, which subsequently may be liberated or become active upon the material being moistened to a proper extent. Finally, a material of this nature is preferred in that, if the pad has been previously used, this will become immediately apparent. It is to be understood, however, in the latter connection, that any material might be employed which, under the action of heat and/or moisture, becomes fragile or distorted to a sufficient extent to render it unfit for further use.

Thus, as in Figures 1 and 2, a heat-conducting layer is indicated at 5. Specifically, this layer may be formed of a foil, such as aluminum, and arranged adjacent thereto may be a sheet of backing paper 6, it being understood, however, that this layer may be dispensed with. Disposed beyond the foil layer is a sheet 7 of, for example, parchment paper or other material which is substantially imperforate and moisture proof, it being here noted that this sheet extends beyond the edges of the sheet 5 so as to provide a closable sealing portion hereinafter referred to.

In turn, disposed in advance of the sheet 7, are one or more layers of pad material as indicated at 8, these layers being, for example, pulp paper, it being understood that in manufacturing the same, any desired thickness of material is provided and that such material may incorporate chemicals, as by impregnation, if desired, which, upon becoming active as, for example, by the use of moisture, are suitable for the treatment. The several sheets or layers 5 to 8 are secured to each other in any convenient manner, it being preferred, according to the present invention, to employ

staples 9 for this purpose which, when the pad is in use, will preferably be so disposed that they will not transmit heat directly to the hair, resulting in its possible injury.

5 In using a pad of this nature the hair is washed and/or treated in any desirable manner and is thereafter coiled upon a spindle 10. The pad portion 8 may now be dipped into a suitable hair treating solution, or if this portion of the article be previously impregnated with chemicals it will only be necessary to dip the sheet 8 into fluid in order to render the treatment efficacious. Thereupon, the entire pad is coiled properly around the tress 15 of hair, care being taken that a portion of the sheet 7 extends beyond the pad proper so that a clip 11 may be applied thereto to close the same to provide a seal, preventing the escape of steam towards the scalp of the person 20 being treated. The pad is enclosed in a heater diagrammatically indicated at 12 and the treatment may now begin.

Obviously, the treatment will proceed in the usual manner, it being noted that due to the 25 relatively high moisture-absorbing and retaining qualities of the pad, that a proper treatment will at all times be assured. Also, obviously, after the treatment has been completed and the pad attached it will be found 30 that the latter, and particularly the portion 8 thereof, will be unfit for further use, rendering it necessary for an operator to discard the pad.

In the form of device shown in Figures 3 35 and 4, an exterior sheet 13 is employed which extends materially beyond the pad proper, indicated at 14, these elements being secured together as, for example, by staples 15. In order that all danger in connection with the use 40 of the pad may be avoided, the sheet 13 is impregnated with a suitable fireproofing substance such as, for example, acetate cellulose. In fact, according to the present invention, it is preferred that such impregnation may be 45 effected at the time of imprinting the exterior sheet of the pad, in which case the fire-proofing substance will, as has been indicated at 16, penetrate the upper surface of the layer 13 to a sufficient depth to assure against accident. 50 In Figure 4 it will also be noted that the pulp paper, i. e. the pad proper, preferably embraces in its body, fibres 17 which may be of cotton and which will serve to prevent a disintegration or tearing of the pad during its 55 initial handling before, or during treatment. It will be understood, however, that such reinforcement will in no way influence the fact that the pad may not be employed repeatedly in the treatment of different persons' hair.

60 Thus, among others, the several objects of the invention specifically aforementioned are achieved. It is intended that numerous changes in construction may be resorted to without departing from the spirit of the invention.

Having described my invention, what I claim as new and desire to secure by Letters Patent is:—

1. As an article of manufacture a hair waving pad including a plurality of sheets, 70 means for securing said sheets to each other and one of said sheets comprising a single comparatively thick layer of substantially highly digested material having relatively high moisture absorption and retaining qualities. 75

2. As an article of manufacture a pad-sheet for use in hair waving and comprising a self-destructive layer of material having incorporated in its body a chemical to become active in the presence of moisture and heat. 80

3. As an article of manufacture a hair waving pad including a plurality of sheets, means for securing said sheets to each other and one of said sheets comprising a body which is 85 substantially self-destructive under the action of moisture and heat.

4. As an article of manufacture a hair waving pad including a plurality of sheets, 90 means for securing said sheets to each other and one of said sheets comprising a body having moisture absorbing and retaining characteristics and formed of a material which is substantially self-destructive under the action of moisture and heat. 95

5. As an article of manufacture a pad-sheet for use in hair waving and comprising a body having moisture absorbing and retaining characteristics and formed of a material which is substantially self-destructive under 100 the action of moisture and heat and means for reinforcing such sheet. 100

6. As an article of manufacture a pad-sheet for use in hair waving and comprising a body having moisture absorbing and retaining 105 characteristics and formed of a material which is substantially self-destructive under the action of moisture and heat and means incorporated within the body of such sheet for reinforcing the same against injury by 110 casual handling. 110

7. As an article of manufacture a pad-sheet for use in hair waving and comprising a body having moisture absorbing and retaining characteristics and formed of a material 115 which is substantially self-destructive under the action of moisture and heat and fibres formed of a different material and incorporated within said body for preventing an injury to such sheet incident to ordinary handling thereof. 120

8. As an article of manufacture a pad-sheet for use in hair waving, and comprising a layer of pulp-paper and fibres extending with such sheet of material to reinforce the same against disintegration under the action of moisture. 125

9. A pad including a sheet to be used in connection with hair waving, such sheet being formed of material which, subsequently to 130

being acted upon by heat and/or moisture, will disintegrate, and means for preventing such disintegration prior to the completion of that step in the permanent waving of hair in connection with which it is employed.

10. A hair-waving pad, including a sheet of material formed to substantially prevent the passage of fluid, and the body of such sheet being impregnated with a fire-proofing substance.

11. A hair-waving pad, including a sheet of material having its outer face imprinted with fire-proofing material to prevent the destruction of such sheet under the action of heat, and a pad-sheet associated with such first-named sheet.

12. A hair waving pad including a sheet of sealing material, a sheet of treating material, means for securing such sheets to each other and such treating sheet comprising a normally flat body formed of pulp paper.

13. A hair waving pad including a sheet of sealing material, a sheet of treating material, means for securing such sheets to each other and such treating sheet comprising a normally flat body formed of pulp paper self-destructive under the action of moisture and heat and means associated with said latter sheet for reinforcing the body thereof.

14. A pad for use in hair waving and to be encircled by a heater, said pad comprising a plurality of sheets of material, a metallic means for securing said sheets to each other and said pad being of a length adequate to be coiled around a tress of hair and to provide a layer between said metallic means and said tress to prevent the transmission of heat to the latter from said heater.

In testimony whereof I affix my signature.
JAMES CHESTER BROWN.
